UNITED STATES PATENT OFFICE.

JOHN F. STANDISH, OF WINTHROP, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

MACHINE FOR OPERATING ON HEELS.

1,269,654.

Specification of Letters Patent. Patented June 18, 1918.

Application filed February 23, 1915. Serial No. 9,968.

To all whom it may concern:

Be it known that I, JOHN F. STANDISH, a citizen of the United States, residing at Winthrop, in the county of Suffolk and State of Massachusetts, have invented certain Improvements in Machines for Operating on Heels, of which the following description, in connection with the accompanying drawings, is a specification, like reference characters on the drawings indicating like parts in the several figures.

This invention relates to machines for operating on the heels of boots and shoes and is herein shown as embodied in a machine for attaching wooden heels although many of its features could be embodied with good advantage in machines for attaching heels of other types or in machines for performing other operations on heels.

In attaching wooden heels it is the practice to drive the attaching nails from within the shoe while the heel is supported upon the heel seat portion of the outsole. It is important to hold the heel firmly in the proper position during the driving operation although the pitch and shape of the heel renders this extremely difficult. One feature of the present invention relates to improvements in the heel holding elements of the machine. As herein shown a head is provided for supporting the heel against the thrust of the drivers and separate members are arranged to engage the surfaces of the heel which face toward the head; *i. e.*, the tread face and the rear sloping surface of the heel, said members being movable to adjust themselves automatically to the contour of heels of various shapes and to maintain their adjusted positions rigidly during the operation of the drivers. Heretofore separate heel engaging members have been provided but it has been necessary for the operator to adjust each of the members by hand in accordance with the size and shape of the particular heel being operated upon and, as there is likely to be considerable variation in these respects, the operation of the machine has been necessarily slow.

One satisfactory form of heel holding

mechanism is herein disclosed and comprises a pair of heel engaging members connected by a pinion meshing with racks formed in the respective members, together with a spring tending at all times to move one of the members toward the heel. When the heel is brought into engagement with this member the pinion is rotated and the other member advanced, relative movement of the two continuing until the pressure thereof is equalized.

Another feature of the invention relates more especially to the driving or pricking mechanism and consists in means for adjustably retaining and guiding the gang of tools which operate upon the heel. It is important to locate the attaching nails at a predetermined distance from the contour of the heel regardless of the size thereof. The best results are secured by locating the nails as near the edge of the heel as possible without danger of driving them out through the surface of the heel or splitting the heel. These conditions call for an accurate and symmetrical adjustment of the drivers and one which may be effected conveniently and rapidly by the operator. In the illustrated embodiment of the invention five drivers are arranged in a pentagonal figure and so mounted that they may be transversely adjusted while maintaining at all times their symmetrical pentagonal arrangement.

Another important feature of the invention consists in the provision of gage members adjustable in accordance with the adjustment of the drivers for the purpose of locating the shoe, and consequently the heel, symmetrically with respect to the outermost drivers. The gage members also assist in insuring a uniform and predetermined distance between the periphery of the heel and the attaching nails in shoes of various sizes.

These and other features of the invention will be best understood and appreciated from the following description of a preferred embodiment thereof selected for purposes of illustration and shown in the accompanying drawings, in which,—

Figure 1 is a view in side elevation, partly

in section, of so much of the machine as is necessary to understand the operation thereof;

Fig. 2 is a sectional view showing the shoe 5 in position upon the jack;

Fig. 3 is a view in perspective of the jack top;

Fig. 4 is a view in perspective of the driver adjusting mechanism;

10 Fig. 5 is a view in perspective of the driver carrying plunger and one of the drivers;

Fig. 6 is a fragmentary sectional view at right angles to that shown in Fig. 2, and

15 Fig. 7 is a diagrammatic view illustrating the range of adjustment of the drivers.

The embodiment of the invention herein illustrated is shown as applied to a heel attaching machine of the type disclosed in United States Patent No. 1,081,917 granted 20 December 16, 1913 on an application of E. A. Tripp. Those parts of the machine not herein illustrated may correspond substantially to the similar parts disclosed in said patent.

25 The machine frame 2 is provided with a stationary support 3 for the jack 4 in which the drivers are mounted. The jack is shaped to support a shoe in an inverted position beneath the movable head 6 which is mounted to slide vertically in suitable 30 ways formed in the frame 2. The head 6 is arranged to be moved downwardly to support the heel against the thrust of the drivers and for this purpose is provided with a roller which runs upon the periphery 35 of a spiral cam 8 journaled in stationary bearings on the machine frame 2 and geared to a rack which is operated by a vertically extending rod 10. The rod 10, as in the patent above referred to, may be depressed 40 by the operator through a treadle, not shown, at the base of the frame.

45 The function of the head 6 is to press the loose heel upon the heel seat of a shoe positioned on the jack and to maintain the heel in position without slipping during the driving operation. To this end the head is provided at its lower side with horizontal guideways in which is mounted a carriage 12 for the heel holding members. The carriage 12 at its forward end is provided with a rod 14 upon which is threaded an adjusting wheel 16. The wheel 16 has a grooved hub which receives a circular rib 50 projecting from the head 6 by which it is held in position longitudinally while permitting the rotary movement to shift the carriage 12 back and forth longitudinally of the shoe.

60 The carriage 12 is provided with two parallel vertical guideways in one of which is slidably mounted the shank piece 18 of the member which engages the tread face of the

heel. The tread engaging member itself comprises a block 20 curved at its upper edge and fitted for adjusting movement in 65 a curved guideway in the shank piece 18. The upper edge of the block 20 is provided with gear teeth which mesh with the teeth of a worm 24 mounted in the shank piece 18. The angular position of the tread engaging 70 face of the block 20 may be adjusted to suit the requirements of the work by turning the worm 24.

In the rearmost guideway in the carriage 12 is mounted the shank piece 26 of a forked 75 member 28 which is shaped to engage the rear curved surface of the heel. The forked member 28 is pivotally mounted in the shank piece 26 and is held in position by a locking nut 32. When the latter is loosened the angular position of the forked member may be varied and its adjusted position maintained by tightening the nut 32. At its lower end the forked member 28 is provided with a facing of yielding material, such as leather, 80 to prevent scratching of the polished surface of the heel.

It will be apparent that the shape and relation of the tread face and the rear curved surface of the heel will vary considerably in 90 changing from one size of shoe to another or on account of differences in height or style of the heels. The two heels engaging members above discussed are arranged to adjust themselves automatically to the heel being operated upon regardless of its shape or style. To this end the proximate faces of the shank pieces 18 and 26 are provided with 95 rack teeth which mesh upon opposite sides of a pinion 40 journaled in the carriage 100 12. With this construction it will be seen that the movement of one heel engaging member is transmitted to the other as an equal movement in the opposite direction.

The shank piece 18 is bored out to receive a 105 spring 38 which bears at its upper end upon a cover plate 34 bolted to the carriage and tends normally to move the block 20 downwardly. An adjusting screw 36 is set in the cover plate 34 in position to engage the upper end of the shank piece 26 and so determine the initial position of both heel engaging members. The spring 38, it will be understood, moves the tread engaging member 110 downwardly and the forked member 28 upwardly until the adjusting screw 36 is engaged and the initial relative position of these two members is so determined that the tread face of the heel shall engage the block 20 before the forked member 28 is 115 engaged by the rear surface of the heel. When the head 6 is depressed therefore the block 20 is moved upwardly in the head 12 and the forked member moved downwardly 120

until it engages the heel, the relative movement continuing until the pressure of the two members upon the heel is evenly balanced.

5 The jack 4 has secured to its upper end a pair of spaced plates 50 and 52 shaped to conform to the contour of the inside of a shoe of the smallest size to be operated upon. The plates are provided with parallel slots 10 through which extend driver guiding tubes 54 for the drivers 48. The drivers 48 are carried by a reciprocatory plunger 42 which has secured to its upper end a plate 44 spaced from the body of the plunger by distance pieces 46. The plate 44 is provided with a slot extending from front to rear, for receiving the rearmost driver, and with divergent slots 45 for receiving the side drivers. As herein shown five drivers are provided, this being the number usually employed, although it would be within the scope of the invention to employ any desired number of drivers. Each of the drivers 48 has secured to its lower end 20 a block 49 having square sides which extend up through the slots in the plate 44 permitting the drivers to be adjusted on the flat driver engaging face of the plunger in the direction of the slots. The upper ends 25 of the drivers are beveled slightly as shown in Fig. 2 to cause the attaching nails to enter the heel in a convergent manner.

The drivers are loose on the plunger 42 and are maintained in the desired position 30 by the guiding tubes 54 which are adjustably but rigidly held in place during the operation of the machine. Each of the side driver guiding tubes 54 is rigidly set in a gage block 56 which is received between the two spaced plates 50 and 52 of the jack top. The gage blocks are so shaped as to permit the guiding tubes 54 to slide transversely but to eliminate angular movement thereof. When the drivers are adjusted for operating 40 upon shoes of the smallest size the blocks 56 fit together and the position of the tubes and drivers is indicated by the small pentagon shown in dash lines in Fig. 7.

The outer edges of the gage blocks 56 are 50 intended to contact with the sides of the shoe being operated upon and to locate the same symmetrically with respect to the drivers and the attaching nails driven by them. These blocks also act to limit the 55 distance between the attaching nails and the edge of the work and are so proportioned as to bring the attaching nails as close to the edge of the heel as is practical without danger of the nails splitting the heel or 60 driving out through its side surfaces. When the guiding tubes 54 are adjusted for the largest shoe the drivers occupy the positions

indicated in Fig. 7 by the large pentagon shown in dotted lines while the outline of the gage blocks corresponding to this adjusted position is also indicated.

Ordinarily it is necessary only to adjust the side drivers as the distance from the rear of the heel to the rearmost attaching nail requires but slight adjustment in heels 65 of various sizes. As herein shown the guiding tube for the rear driver is threaded at its upper end to receive a set nut 62 by which the tube may be clamped rigidly to the plate 52. The slot 53, however, permits 70 adjustment of this tube and the corresponding driver longitudinally of the shoe. The side drivers are simultaneously adjusted by the movement of a slotted frame 58 which is mounted beneath the fixed plate 50 and 75 provided with an adjusting screw 60 by which it may be moved from front to rear. The frame 58 has slots extending substantially at right angles to the guide slots in the fixed plates and the guiding tubes pass 80 through these slots in the frame. When the adjusting screw 60 is turned to move the frame 58 forwardly, the side drivers are moved positively in that direction and are 85 caused to follow the direction of the guide 90 slots. These are so shaped as to maintain the guiding tubes at all times in a symmetrical polygon.

At their upper ends the guiding tubes 95 54 are provided with conical heads which engage directly with the heel seat portion of the insole of the shoe. As the drivers are arranged to move to the end of the guiding tubes this construction insures that the attaching nails shall be driven with their heads flush with the insole regardless of the transverse curvature of the sole. This results from the fact that the sole is supported on a number of isolated points of small dimension and does not have to be 100 conformed to a plate which may not coincide with its curvature.

In placing a shoe upon the jack it sometimes happens that the operator will bear 105 down upon the forward portion thereof and break a shank downwardly while the heel seat portion is clamped between the heel and the jack top. To eliminate such occurrence there is provided a supporting member 68 having a flat end arranged to bear upon the inside of the shoe shank as shown, 110 in Fig. 2. For purposes of adjustment a vertical slot 66 is provided in a rib formed on the forward side of the jack post and the support 68 is clamped in adjusted position by a clamping bolt 69.

In operating the machine herein described the shoe to be heeled is placed upon the jack 4 as shown in Figs. 1 and 2 and the

adjusting screw 60 turned to bring the gage blocks 56 into engagement with the inside of the shoe, this adjustment properly locating the drivers for the shoe to be operated upon. The head 6 is then depressed through the treadle rod 10 until the engaging members 20 and 28 have been brought into even bearing upon the tread and rear surface of the heel. While the head is maintained in this position the machine is started and the drivers elevated forcing the attaching nails through the sole and into the heel. The operation may then be repeated and no further adjustments are necessary until it is desired to operate upon shoes of a different size.

Having thus described my invention, I claim as new and desire to secure by Letters Patent of the United States:

- 20 1. A machine for operating on heels, having, in combination, a gang of drivers including a rear driver and side drivers adjustable bodily toward and from each other for heels of various sizes, a guiding tube for each side driver adjustable bodily with its respective driver, means for simultaneously adjusting the side driver tubes and drivers, and means for adjusting the rear driver independently of the side drivers.
- 30 2. A machine for operating on heels, having, in combination, a gang of tools, and heel holding means including a tread engaging member and a member for engaging the rear sloping surface of a heel, said members being so connected as to insure automatically the application of an equal degree of pressure on heels of various shapes.
- 40 3. A machine for operating on heels, having, in combination, a gang of tools, and means for holding a heel against the thrust of the tools including a carriage movable bodily transversely to the path of the tools, a pair of heel engaging members mounted in said carriage, and connections between said members constructed and arranged to impart the movement of one member to the other.
- 50 4. A machine for operating on heels, having, in combination, a gang of tools, and means for supporting a heel against the thrust of the tools including coöperating heel engaging members arranged for movement in parallel paths, each of said members having provision for independent angular adjustment about axes disposed transversely to the heel, and a pivoted connection interposed between said members.

- 60 5. A machine for operating on heels, having, in combination, a gang of tools, and means for supporting a heel against the thrust of the tools including a pair of heel engaging members disposed side by side, and

a spring tending to move one of said members toward the heel and the other away from it.

6. A machine for operating on heels, having, in combination, a tread engaging member, a spring tending to move said member toward a heel, and a second member for engaging the sloping surface of the heel adjustable in response to the movements of the tread engaging member.

7. A machine for operating on heels, having, in combination, a flat heel engaging member, a spring tending to move said member toward a heel, a forked heel engaging member also acted upon by said spring, and an adjustable stop for determining the initial position of both members.

8. A machine for operating on heels, having, in combination, a movable head, a flat tread engaging member arranged for angular adjustment about an axis parallel to the tread, and a forked heel engaging member, both movably mounted in the head, and connections between said members for equalizing their pressure on heels of various shapes when the head is moved toward a heel.

9. A machine for operating on heels, having, in combination, a gang of tools, and a head for resisting the thrust of the tools, having parallel guideways formed therein, a slide movable in each guideway, a member on each slide for engaging the surfaces of the heel which face toward the head, said slides being movable to permit the heel engaging members to adjust themselves automatically to the contour of heels of various shapes and to maintain their adjusted positions rigidly during the operation of the tools.

10. A machine for operating on heels, having, in combination, a jack for a shoe, a head movable toward and from the jack, parallel guideways in the head, a member movable in each guideway and having an angularly adjustable heel engaging portion, a rack formed in each member, an interposed gear meshing with both racks, and means to move the head into position for pressing a heel upon the shoe on the jack.

11. A machine for operating on heels, having, in combination, coöperating heel holding members, a gang of tools, a guiding device associated with each tool, and means for simultaneously adjusting said tools and guiding devices substantially independently of the heel holding members.

12. A machine for operating on heels, having, in combination, heel holding means, and a gang of tools arranged in a pentagonal figure with a single tool located at the rear of the heel, the remaining tools being transversely adjustable with respect to the rear

- tool in directions such that a symmetrical pentagonal figure is maintained in all adjusted positions of the tools. 13. A machine for operating on heels, having in combination, heel holding means, a gang of drivers including a rear driver, and side drivers adjustable transversely with respect to the rear driver, and means for guiding the side drivers in paths extending divergently away from the rear driver. 14. A machine for operating on heels, having, in combination, heel holding means, a gang of drivers including a rear driver mounted for adjustment, from front to rear, and side drivers mounted for adjustment in divergent paths which extend in general direction away from the rear driver. 15. A machine for operating on heels, having, in combination, heel holding means, a gang of drivers including a rear driver, side drivers transversely adjustable toward the rear driver in convergent paths, and means for simultaneously adjusting all of the side drivers independently of the rear driver. 16. A machine for operating on heels, having, in combination, heel holding means including a jack, a plunger mounted to reciprocate in the jack and having a slotted head, tools adjustably retained upon the plunger by the slots of the head, and a stationary plate secured to the jack and having correspondingly shaped slots whereby the outer ends of the tools are adjustably retained in place. 17. A machine for operating on heels, having, in combination, tool guiding devices, a plate having slots diverging toward the breast of the heel to be operated upon and being arranged for adjustably retaining the guiding devices, and an adjusting slide connected to said devices and movable in a path extending longitudinally of the heel. 18. A machine for operating on heels, having, in combination, a hollow post, a plunger arranged to reciprocate within the post and having a flat driver engaging face, drivers resting upon said face, driver guiding tubes adjustably mounted in the upper end of the post and extending downwardly within the post toward the plunger, and means for moving certain tubes inwardly or outwardly with their corresponding drivers, thereby sliding the drivers into different positions on the face of the plunger. 19. A machine for operating on heels, having, in combination, heel holding means, a support, a gang of separate nail receiving tubes adjustably carried in the support, and means for gaging the location of the tubes with respect to the contour of the heel to be operated upon, whereby the nails may be located at a predetermined distance from the contour of heels of various shapes. 20. A machine for operating on heels, having, in combination, heel holding means, a gang of transversely adjustable drivers, and a separate guiding tube for each driver having an associated gaging member for maintaining the guiding tube and its associated driver at a predetermined distance from the contour of the heel to be operated upon regardless of its size. 21. A machine for operating on heels, having, in combination, a stationary post, a gang of relatively adjustable drivers, guiding tubes for the drivers movable in the post, and gage members symmetrically adjustable with respect to their effective width in accordance with the spread of the drivers, whereby the outermost drivers are maintained equal distances within the side edges of the heel. 22. A machine for operating on heels, having, in combination, a jack arranged to enter a shoe and having nail drivers mounted therein, and nail receiving tubes movable in the jack, the jack top shaped to conform to the inside of the shoe and having transversely adjustable gage members movable with the nail receiving tubes to accommodate shoes of various sizes. 23. A machine for operating on heels, having, in combination, a jack arranged to enter a shoe, a driver adjustably maintained in position adjacent to the rear end of a heel to be operated upon, side drivers transversely adjustable in the jack, guiding tubes for the drivers, and means for limiting the distance between the side drivers and the sides of the shoe being operated upon. 24. A machine for operating on heels, comprising a series of work supporting members having edge gaging faces, means to adjust said members transversely of said faces, drivers reciprocally mounted in said members and movable transversely therewith, and a reciprocally movable operating device for said drivers having a transverse engaging face therefor, arranged to be engaged at different points by said drivers in different positions of adjustment thereof. 25. A machine for operating on heels, comprising a series of work supporting members having edge gaging faces, means to adjust said members to move said faces transversely for heels of different sizes, a reciprocally movable driver actuating plunger having a transverse driver engaging face, and a series of drivers reciprocally mounted in said work supporting members and actuated to be held in engagement with said engaging face and transversely movable to different positions thereon by said sup-

porting members when the latter are adjusted.

26. A machine for operating on heels, having, in combination, a gang of tools, and 5 heel holding means comprising a member for engaging the tread surface of a heel, and a member for engaging the rear sloping surface of a heel, and equalizing connections between said members constructed to 10 insure automatically that both of said members shall engage firmly the respective tread and sloping rear surfaces of heels of various sizes or shapes.
27. In a machine for operating upon 15 pitched heels, means for holding a heel against movement by engagement with its tread surface and its sloping rear surface,

comprising a tread engaging member and a member for engaging said sloping surface, said members being so interconnected that 20 engagement of one of them with the heel will cause the other to approach the heel until both members engage firmly the respective surfaces of the heel, to hold it against displacement, regardless of its size 25 or shape.

In testimony whereof I have signed my name to this specification in the presence of two subscribing witnesses.
